DESIGN FOR A BELT CLASP

Viola T. Howard, Saylesville, R. I., assignor to
Swank Products, Inc., a corporation of Delaware

Application July 2, 1938, Serial No. 78,246

Term of patent 14 years

To all whom it may concern:

Be it known that I, Viola T. Howard, a citizen of the United States of America, residing at Saylesville, county of Providence, State of Rhode Island, have invented a new, original, and ornamental Design for a Belt Clasp, of which the following is a specification, reference being had to the accompanying drawing, forming a part thereof.

Fig. 1 is a front elevational view of a belt clasp showing my new design;

Fig. 2 is a rear elevation;
Fig. 3 is a side elevation;
Fig. 4 is a section on line 4—4 of Fig. 3; and
Fig. 5 is a sectional view on line 5—5 of Fig. 3.
The important feature of the design is that shown in full lines.

I claim:

The ornamental design for a belt clasp, substantially as shown and described.

VIOLA T. HOWARD.
